UNITED STATES PATENT OFFICE.

NANNIE G. DAVIS, OF WASHINGTON, DISTRICT OF COLUMBIA.

DESIGN FOR A SPOON.

SPECIFICATION forming part of Design No. 20,828, dated June 9, 1891.

Application filed May 7, 1891. Serial No. 391,985. Term of patent 3½ years.

To all whom it may concern:

Be it known that I, NANNIE G. DAVIS, a citizen of the United States, residing at Washington, in the District of Columbia, have invented and produced a new and original Design for Spoons, of which the following is a specification, reference being had to the accompanying drawing, forming part thereof.

The figure represents a face view of a spoon having thereon a representation of my design.

The leading feature of my design consists in a representation of a head of Columbus surrounded upon the tip thereof by a partially wreathed frame and a view of the "Santa Maria" in the bowl of the spoon, with the swelled or enlarged part of the handle having

thereupon an oblique panel or scroll for a suitable inscription. At the upper end of the spoon A is arranged a representation of the head of Columbus C, placed in an oval frame, with a laurel wreath extending about half-way of its circumference. In the bowl B of the spoon is placed a representation of a vessel, the "Santa Maria," D, in which Columbus crossed the Atlantic and discovered America.

What I claim is—

The design for a spoon herein shown and described.

NANNIE G. DAVIS.

Witnesses:

W. WACHSMANN,

LUCIUS F. RANDOLPH.
